REFRIGERATING UNIT

Frank R. West, Detroit, Mich.

Application May 21, 1935, Serial No. 22,564

3 Claims. (Cl. 62—89)

This invention relates to a refrigerating unit, and has to do particularly with a refrigerator cabinet having a storage compartment formed separately from the main food compartment.

Heretofore attempts have been made to conserve the relatively cold atmosphere produced in the food chamber by so locating the sharp freezing unit as to be independently accessible from the food compartment, permitting sharp frozen foods to be removed without disturbing, or greatly disturbing, the atmosphere in the food compartment. It is one of the objects of the present invention to conserve the cold atmosphere in the large food compartment by providing a novel, inexpensive auxiliary compartment, cooled by conduction from the main compartment and adapted to receive articles of food most commonly used.

More specifically, the present invention has to do with the adding of an auxiliary compartment to a standard refrigerator cabinet by merely dropping the insulation at the bottom of the cabinet a few inches so as to provide a compartment for receiving a drawer or the like; by dropping the insulation the bottom wall of the refrigerator liner becomes the top wall of the auxiliary compartment and the cooling of the auxiliary compartment is by conduction through the bottom wall of the main food compartment. The main features of my auxiliary compartment are, that it is formed with very little additional expense and without changing the design of the standard refrigerator cabinet, it is sealed from the main compartment, cooling is by conduction from the main compartment, and the most commonly used foods may be properly cooled and removed and replaced without disturbing the main food compartment.

Other features have to do with details of design and construction as will be more clearly brought out in the specification and claims.

In the drawings:

Fig. 1 is a front elevation of a refrigerator cabinet fabricated in accordance with the present invention.

Fig. 2 is a vertical sectional view taken on line 2—2 of Fig. 1, illustrating the preferred relationship of the construction of the main food compartment and auxiliary compartment.

Fig. 3 is a horizontal sectional view taken on line 3—3 of Fig. 2 showing the location of the auxiliary compartment within a continuation of the insulation walls of the cabinet.

Fig. 4 is a modified form of cabinet wherein a second auxiliary compartment is formed as a vertical compartment alongside the main compartment.

Fig. 5 is a section along the line 5—5 of Fig. 4 illustrating one arrangement of shelf and draw-

er structure for this vertical auxiliary compartment.

Fig. 6 is a horizontal sectional view taken on line 6—6 of Fig. 4 illustrating particularly the drawer structure and wall structure of the auxiliary compartment.

Fig. 7 illustrates a further modified form of cabinet structure wherein the auxiliary compartment is sealed from the main compartment but is cooled by air circulating around the auxiliary compartment as well as by conduction around the bottom of the main compartment.

Fig. 8 is a fragmentary sectional view on line 8—8 of Fig. 7 showing the circulating ports between the main compartment and the outside walls of the auxiliary compartment.

Fig. 9 is a sectional plan view taken on line 9—9 of Fig. 8.

In forming my separate storage compartment sealed from but cooled by the main food compartment, I preferably make use of a standard refrigerator cabinet and in Fig. 1 I have shown what might be termed a composite view of several standard makes of refrigerator cabinets, the purpose being to show that my auxiliary storage compartment is adapted to many different types of cabinet structure. In Figs. 1 and 2 the cabinet is generally designated as at 2, the main food compartment 3 and a door therefor as at 4. Circulation of the air within the food compartment 3 to produce cooling thereof is by means of any standard type of cooling unit 5.

Most refrigerator cabinets have a metal porcelain liner 6 with the usual side walls including a bottom wall 7; it is the bottom wall 7 which is the important part of the present invention and in its preferred form this bottom wall or sealing shelf is continued and turned over as at 8 to form a breaker strip for the door 4 as well as the closure member 9, as will be presently described. One of the very important things about any refrigerator cabinet is the insulation, and in carrying out the present invention, instead of redesigning and fabricating an expensive type of cabinet to form the extra auxiliary chamber, I merely drop the insulation 10 a few inches below the bottom wall 7 of the food compartment so that the bottom lining of insulation is positioned as at 11 instead of up against the bottom of the wall 7.

In the average refrigerator cabinet the wall 7 is positioned approximately where it is shown in Fig. 2 and the space between this wall and the bottom of the cabinet is usually waste space. Thus in making up my refrigerator cabinet, I merely drop the insulation 10 down the number of inches required, say, from three and one-half to seven inches, and position therein a lining 12, preferably open at the top as at 13. The front and side walls of this lining 12 are extended as 14

at 14 to provide a breaker strip around the remaining three sides which form the opening for the auxiliary compartment.

The front panel 15 of the refrigerator cabinet 5 is apertured corresponding to the breaker strip formed by the portion 8 and the side and bottom walls 14 and is designed to receive a drawer member 16, the front end of which is attached to and closed by the closure member 9. The auxiliary 10 compartment for receiving the drawer 16 may be generally designated 17. Cooling of the compartment 17 is by means of conduction through the bottom wall 7. In other words, cooling of this bottom wall 7 is by convection, through circulation 15 of air currents over the cooling unit 5, and the cooling of the atmosphere within the compartment 17 is by conduction and convection through contact with the bottom wall 7 of the main food compartment.

It will thus be seen that the compartment 17 20 may be added to the standard type of refrigerator cabinet with very little added expense. The contents thereof are completely sealed from the food compartment 3 and thus sealed from any odors 25 therein. Commonly used foods such as butter, eggs, cheese and the like, may be stored in this lower compartment and kept at the proper temperature without any contamination with any odors in the food compartment proper. Inasmuch 30 as the lower part of the food compartment 3 is cooler than the top part, it will be seen that the compartment 17 will be maintained at a slightly lower temperature than the top of the food compartment 3 but at a higher temperature than the 35 bottom part. In other words, as a common example, the bottom part of the food compartment 3 would be maintained at around 42°, the top part of the compartment at 48°, and the auxiliary compartment 17 at 47° or slightly under. This 40 auxiliary compartment will also be ideal for holding bottled goods not only because of the properly maintained temperature but because it is easier to store bottles therein by laying them on their side, thus making it possible to diminish the distance 45 between the shelves in the main food compartment and store more food.

In the modification illustrated in Figs. 4, 5 and 6, I have added a vertical compartment which 50 may be generally designated 18. This compartment may be constructed similarly to the compartment 17 but if the standard size cabinet is used it will require a slight decrease in the size 55 of the storage cabinet of the main compartment. This compartment may be formed by having a wall 6 of the main food compartment serve as the conducting means for cooling the air in the compartment 18. A metal sleeve 19 may be fitted in this compartment to receive and guide a drawer member 20. This vertical drawer 20 may be provided with suitable racks 21 for positioning and holding various articles of food. The compartment 18 will likewise be sealed from the main compartment 3.

Where desired to maintain the auxiliary compartment at a temperature considerably below that maintained in the auxiliary compartments shown in Figs. 2 and 5, I provide a second liner 12a spaced inwardly at the back, sides and bottom from the liner 12 and preferably sealed to the bottom wall 7 of the main compartment 3. Such a construction provides a circulating space 23 around the back, side and bottom walls of the

auxiliary compartment. In other words, the auxiliary compartment 17, as shown in Figs. 7 to 9, together with the drawer 16 is substantially the same as that shown in Figs. 2 and 5 except slightly smaller so as to provide for the circulating space 23. Apertures 24 are provided at the longitudinal bottom corners in the liner 6 and struck out portions 25 will cover these apertures to prevent food from falling thereinto. It will be seen that with this arrangement that cooled air from the main compartment 3 will circulate around and through the walls 23 to cool the auxiliary compartment 17 in addition to the cooling effect obtained by conduction through the bottom wall 7 of the main compartment.

15

What I claim is:

1. A domestic refrigerating unit having a cabinet with conventional insulated walls, a main food compartment defined by a liner, a cooling unit positioned to cause circulation of air within the main compartment, a closure for said main compartment, a relatively flat auxiliary compartment for small commonly used foods positioned directly adjacent said main compartment and comprising a double walled liner having air spaces between the walls, the top of which is formed by the bottom of said main liner, said auxiliary compartment being sealed from said main compartment, said main liner having openings leading to said air spaces whereby cooling of said auxiliary compartment is by conduction through a portion of the bottom of said main liner and by circulation of air from the main compartment through said openings around said auxiliary compartment.

20

2. A domestic refrigerating unit having a cabinet with conventional insulated walls, a main food compartment defined by a liner, a cooling unit positioned to cause circulation of air within the main compartment, a closure for said main compartment, a sealed, relatively flat, double-walled auxiliary compartment for small commonly used foods positioned directly adjacent a wall of said main compartment whereby cooling of said auxiliary compartment is by conduction through a portion of said wall of said liner and by circulation, between the double walls of said auxiliary compartment, of air from said main compartment, the remaining walls of said auxiliary compartment other than the wall adjacent the main liner being insulated by a continuation of the conventional insulation surrounding the main food compartment.

30

3. In a domestic refrigerator, a cabinet, a main liner defining the main food compartment, a cooling unit in the main compartment for setting up circulation of refrigerated air therein, a separately accessible auxiliary compartment beneath the main compartment comprising a second liner, and a storage compartment formed by a third liner depending from the bottom of said main liner and spaced from said second named liner to permit air flow around said storage compartment, said main compartment liner having openings in its bottom portion communicating with the spaces between said second and third named liners, the inside of said storage compartment being completely sealed from the inside of said main liner and being cooled by conduction through the bottom wall of said main liner and by circulation of air from the main compartment around the storage compartment.
